UNITED STATES PATENT OFFICE.

JOSEPH WEATHERBY, JR., OF NEW CUMBERLAND, PENNSYLVANIA,
ASSIGNOR TO THE WEATHERBY ELECTRIC AND MANUFACTURING COMPANY, OF NEW CUMBERLAND, PENNSYLVANIA, A CORPORATION OF DELAWARE.

SIGNAL MECHANISM FOR BLOCK-SIGNAL SYSTEMS.

SPECIFICATION forming part of Letters Patent No. 772,548, dated October 18, 1904.

Application filed December 10, 1903. Serial No. 184,646. (No model.)

To all whom it may concern:

Be it known that I, JOSEPH WEATHERBY, Jr., a citizen of the United States, residing at New Cumberland, in the county of Cumberland and State of Pennsylvania, have invented certain new and useful Improvements in Signal Mechanism for Block-Signal Systems; and I do declare the following to be a full, clear, and exact description of the invention, such as will enable others skilled in the art to which it appertains to make and use the same.

This invention relates to signal mechanism for block-signal systems, and particularly to signal mechanism of that character in which a semaphore or approved type of signaling device or indicator is electrically operated by a moving car to show whether or not the block is clear, the present device being especially designed for use in connection with electric block-signal systems of the type shown in my prior patent, No. 748,824, dated January 5, 1904.

The object of the invention is to provide a signaling apparatus which is simple of construction, efficient and positive in action, and not liable to become deranged in use and in which the signaling device *per se* is adapted to be projected with a minimum throw of the operating element and to be automatically retracted by gravity, thus dispensing with the use of springs and other elements which are liable to become broken or deleteriously affected by climatic changes.

With these and other objects in view the invention consists of certain novel features of construction, combination, and arrangement of parts, as will be more particularly described, and particularly pointed out in the appended claims, reference being had to the accompanying drawings, in which—

Figure 1 is a view in elevation looking toward one side of my improved signal device. Fig. 2 is an end elevation of the same. Fig. 3 is a vertical section taken on the line 3 3 of Fig. 1. Fig. 4 is a side elevation showing one of the doors of the signal-box thrown open to expose one of the sets of signaling devices. Fig. 5 is a top plan view of one of the doors

and the semaphore and its operating means carried thereby. Fig. 6 is an inner side elevation of the same, and Fig. 7 is an enlarged detail view of the target throwing and releasing means.

Referring to the drawings, 1 represents the signal box or casing, consisting in the present instance of a cylindrical body portion 2, closed at its sides by flat circular or disk shaped doors 3 and 4, which are hinged, as shown at 5, to swing open to the position shown in Fig. 3 and are adapted to be locked in closed position by any preferred type of locking means. These doors form the signal-fronts of the box, which face in opposite directions along the trackway and are provided with sight-openings 3' and 4' to display signals to the in and out bound cars traveling in opposite directions along the trackway. From this it will be observed that the device, as shown, is designed for use on single-track railways having turn-outs; but it will of course be understood that separate boxes for the opposite signals may be used at the junctions or stations for double-track railways. Each box is provided at its base with a hollow pivot-stud or trunnion 6, adapted to fit and turn within a socket 7 upon a bracket 8, mounted upon supporting-post 9, whereby the box may be turned horizontally to set at any desired angle to suit the line of the trackway, a set-screw 10 being provided to impinge against said stud and hold the box firmly in adjusted position. The box supports and contains two sets of signaling devices for the in and out bound cars, respectively. These signaling devices are similar in construction, and as a description of one will suffice for both I will proceed to describe only one of them, which I will term the "outbound" signaling devices, the corresponding parts of the other, or inbound, signaling devices being indicated by corresponding primed numerals of reference. Thus it will be observed that the sight-opening in the door 3, facing the outbound cars, is closed by a glass panel 13, which is held in place by an annular clamping-frame 14, having an inturned annular flange 15, forming a casing or chamber to receive said panel, the lat-

ter being clamped at its edge against opposite cushioned fillers 16, preferably formed by rings of ordinary insulated wire interposed between the panel and the wall of the box and 5 the flange. The frame 14 also has an outer flange 17, through which screws or other like fastenings are passed to secure it to the door, and is provided with a hood 18 to protect said panel and prevent obscuration of the panel 10 by sun or other interfering light-rays.

Extending from the inner side of the door is a bearing or pivot-stud 19, on which turns a hub or sleeve 20, to which is fixed the red target disk or semaphore 21, the said hub or 15 sleeve being detachably held upon the stud by a securing-screw 22. On the hub or sleeve is formed a head 23, having two rows or series of concentric holes or seats 24 and 25 and a contact-pin 26, which is adapted to be fitted 20 into either one of said holes or seats. This pin acts in the nature of a crank, which is acted upon by an operating-arm 27 to project or throw the disk 21, which is restored by gravity to its normal or release position by arms 28 25 and 29, radiating at right angles from the hub 20, said arms carrying adjustable weights 30 and 31, whereby upon the release of the pin 26 by the arm 27 the disk will be swung from its projected position, in which it is in register with the panel 13, as seen in Fig. 6, to its 30 normal position below the panel, as seen in Fig. 3. By means of the adjustable connection of the pin 26 and the weights 30 and 31 the throw of the target-disk may be easily 35 regulated and a sensitiveness of action secured to accord with the extent of throw or movement of the arm 27. Moreover, this construction enables the target-disk to be projected with a minimum throw of the operating-arm 40 and movement of its actuating-armature and dispenses with the use of retracting-springs or other elements which are liable to be deteriorously affected by climatic changes. Stops 45 32 and 33, respectively, limit the up and down movements of the target-disk.

The arm 27 is carried by the pivoted armature 34 of a controlling-electromagnet 35, mounted in a suitable supporting-frame 36, secured to the inner side of the door, said 50 armature being pivoted at 27' to said frame. When said magnet is energized and attracts the armature, the arm 27 is swung on the pivot 27' to throw the target-disk. On the other hand, when the magnet is deenergized 55 and the armature moves outward therefrom the weighted arms swing the target-disk back to its normal position. It will be observed that the target-disk and the means for directly operating the same are mounted upon the door, 60 so that by simply swinging the door open access may be conveniently obtained to said disk and operating means for repairing or renewing injured or worn-out parts. It will also be observed that the arm 27 is not mechanically 65 connected to the pin 26, but has a sliding or

shifting engagement with the same. This allows the pin to move freely in a curved path in a plane at an angle to the movement of and relatively to the arm without binding of the arm or any connecting part, thus making it 70 easier of operation than if it had a positive mechanical connection with the arm.

On the interior of the body portion 2 of the box or casing are incandescent or equivalent lamps 37, in rear of which is a background or reflector 38. This background or reflector preferably consists of a white panel of porcelain or frosted glass and is interposed between the two sight-openings 3' and 4', so that it will act as a background or reflector for both sets 75 of lamps and signaling devices. The light from the lamps shows white through the sight-panel or bull's-eye 13 when the target-disk is lowered and red when said target-disk is elevated to come between the lamps and sight-panel. By the use of a white background or reflector of the character stated both the white or colorless light and the red light are made to show with great distinctness for a considerable distance from the box or station, thereby 80 increasing the effectiveness of the signal. As shown, the white background or reflector-panel is supported intermediate the two sets 85 of lamps 37 and 37' by hangers 39, suitably secured to the casing-body 2. The lamps and 90 electromagnets are included in an electric circuit, of which only the conductors are herein shown, the leaders or supply members 40 of said conductors extending to the exterior 95 through the hollow pivot-stud 6. In order to 100 protect the lamps and electromagnets against lightning and other electrical currents of abnormal strength, a fuse or terminal block 41 is provided at one end of the box or casing.

The various wires connecting the lamps and 105 electromagnets are attached to binding-posts or terminals 42 upon said block 41, and said terminals are connected by fuses 43, as clearly 110 shown in Figs. 3 and 4. A lightning-arrester strip 44, having a ground connection through 115 the box or casing and the post on which the latter is mounted, is also secured to said block 41 adjacent to said terminals or binding-posts 42. The signal mechanism, as shown, is 120 designed to operate upon the regular trolley-circuit of five hundred and fifty volts direct; but it will be understood that the same may be adapted to be operated by any voltage by increasing or decreasing the number of incandescent lamps in circuit with the magnets. In 125 practice the operating connections may be of the type shown in my prior patent, No. 748,824, before referred to, in which circuit-closers operated by the trolleys of the cars control circuit make and break devices which 130 govern the operation of the target-operating magnets in such manner that the in and out bound signals will be set and retracted by cars traveling in opposite directions to indicate when each block is occupied and when it is

clear. These connections are not herein shown, for the reason that they form no part of the present invention, which relates to the signal device *per se*.

5 A casing 45 is mounted on the top of the signal-box, with openings at both ends in which clear glass panels 46 and 47 are placed. A partition 48 is placed in the middle of the casing to prevent light from either side penetrating to the opposite chamber. Lamps 49 and 50 are provided in both chambers, connected by wires 51, 52, and 53. The object of these lamps is to provide a signal to an approaching car to show if another car has preceded it in 15 the block. The action of the same is as follows: When a car enters the block, it sets a red signal at the far end of the block and releases a red signal at the near end of the block and at the same time lights the lamp 50, if the 20 car enters the block facing in that direction, or lamp 49, if it enters in the opposite direction at the near end of the block. Should a second car now follow the first car in block, a warning to proceed with caution is given by 25 the fact that the lamp 49 or 50 is burning. The lamps 49 and 50 are preferably colored green, so as to have a separate color for each signal. A green semaphore may replace the lamps inside the signal-box, mounted along- 30 side the red semaphore, without departing from the principle stated. The lamps 49 and 50 are connected in series by the leads 51, 52, and 53 with the signals in the far ends of the block in both directions.

35 From the foregoing description, taken in connection with the accompanying drawings, the construction and operation of the invention will be readily understood without requiring a more extended explanation.

40 Various changes in the form, proportion, and the minor details of construction may be resorted to without departing from the principle or sacrificing any of the advantages of this invention.

45 Having thus described my invention, what I claim as new, and desire to secure by Letters Patent, is—

1. A signal apparatus having a sight-opening, a combined signal and reflector behind 50 said opening, a target adapted to come between said signal and reflector and the sight-opening, and a light-generator between the sight-opening and the said signal and reflector, and adapted to be arranged between the latter 55 and target when said target is moved into register with the sight-opening, substantially as described.

2. A signal apparatus comprising a casing having a sight-opening, a white reflector in 60 rear thereof, a red target-disk adapted to be interposed between the sight-opening and reflector, and a light-generator between the reflector and plane of motion of the target-disk, substantially as described.

65 3. A signal apparatus comprising a casing

having opposite sight-openings, a reflector between and common to said openings, light-generators on opposite sides of said reflector, and targets adapted to move between the said light-generators and sight-openings, substantially as described. 70

4. In a signal apparatus, the combination with a supporting member provided with a socket, of a signal-lantern containing an electric illuminator and having a trunnion fitting 75 in said socket and adapted to turn therein to permit said lantern to be set to correspond to the line of the trackway, lead-wires extending through said hollow trunnion and into the lantern, and means for holding the trunnion 80 against movement and the lantern in adjusted position, substantially as described.

5. A signal apparatus comprising a casing, a door hinged thereto and provided with a sight-opening, light-supplying means arranged within the casing, and semaphore mechanism carried by the door and accessible 85 when the door is swung open, substantially as described.

6. An electric railway-signal having a controlling-magnet, an armature operated thereby, a swinging target having a crank member, and a vibrating arm actuated by the armature and in sliding engagement with the crank member, whereby, when the arm is vibrated, the said crank member may move in a curved path and relatively to the arm without connection therewith to set or retract said swinging target, substantially as described. 90

7. An electric signal comprising a counter- 100 balanced rotary member, a semaphore extending radially therefrom and adapted by its excess of weight to assume by gravity a normal or retracted position, a crank-pin projecting from the side of the rotary member at right angles to said semaphore, an electromagnet, 105 an armature operated thereby, and an arm actuated by the armature and actuating said crank-pin, substantially as described.

8. An electric railway-signal having a controlling-magnet, an armature operated thereby, a rotary member, a target carried by the rotary member, a crank-pin radially adjustable upon the rotary member, and an arm operated by the armature to engage and operate the crank-pin and having a shifting engagement with said crank-pin, substantially 115 as described.

9. An electric railway-signal having a controlling-magnet, an armature operated thereby, a rotary member, a target carried by the rotary member, a crank-pin radially and circumferentially adjustable upon the rotary member, an arm operated by the armature to engage and operate the crank-pin, and having a shifting engagement with said crank-pin, substantially as described. 120

10. An electric railway-signal having a controlling-magnet, a pivoted armature operated thereby, a rotary member provided with a 130

head or disk, a target carried by the rotary member, a crank-pin adjustably mounted upon said head or disk, and an arm carried by the armature to engage and operate said crank-pin to project the target, substantially as described.

11. An electric railway-signal comprising a signal-box, a casing upon said signal-box, lamps respectively in said box and casing, and conductors extending into the box and casing for supplying an electric current to said lamps, substantially as described.

12. An electric railway-signal having a controlling-magnet, a rotary member provided with radially and circumferentially arranged seats, a crank-pin adapted to engage either of said seats, and an arm operated by the magnet and adapted to operate said crank-pin,

20 said arm having a shifting engagement with said pin, substantially as described.

13. An electric railway-signal having a controlling-magnet, a rotary member, an armature operated by the magnet, and an operating connection between said rotary member and magnet, said connection comprising members, one having a shifting engagement with the other member and an adjustable connection with the rotary member, substantially as described.

25 In testimony whereof I have hereunto set 30 my hand in presence of two subscribing witnesses.
